UNITED STATES PATENT OFFICE.

HARRY E. MARSHALL, OF HIGHLAND PARK, MICHIGAN.

LINEMAN'S SHOE.

1,185,119.

Specification of Letters Patent. Patented May 30, 1916.

Application filed December 4, 1915. Serial No. 64,949.

To all whom it may concern:

Be it known that I, HARRY E. MARSHALL, a citizen of the United States, residing at Highland Park, county of Wayne, State of Michigan, have invented a certain new and useful Improvement in Linemen's Shoes, and declare the following to be a full, clear, and exact description of the same, such as will enable others skilled in the art to which it pertains to make and use the same, reference being had to the accompanying drawings, which form a part of this specification.

This invention relates to shoes for line-men employed in repairing or working on lines carrying electric current.

The object of the invention is an insulating shoe which is constructed to afford a very high resistance to the passage of electric current, as for instance, a resistance which will prevent the passage of a current of 30,000 volts and upward.

The shoe is constructed in such a way as to give a visible warning when worn to a point where its resisting efficiency is lowered. The shoe is also constructed in such a way as to prevent the registry of blow-holes in the rubber insulating medium which might easily break down when subjected to smaller currents than those for which the shoe is tested.

In the drawings,—Figure 1 is a side elevation of the shoe. Fig. 2 is a vertical longitudinal section of the lower part of the shoe. Fig. 3 is a front view of the lower part of the shoe with a half of the same sectioned.

a designates the tap which is constructed preferably of white rubber having high wearing properties.

b is an insulating sole constructed preferably of brown rubber which has a high electrical-resistance efficiency.

c represents a number of layers of waterproof material constructed of a compound made of scrap, such as cork, reclaimed rubber and like materials which are ground up and formed into a compound which is lighter than solid rubber and yet waterproof. The idea of these layers is only to form a sort of filler material which is waterproof and yet lighter than solid rubber.

d represents the fabric on the inside of the sole which lines the same.

e designates the heel constructed preferably of brown rubber.

It will be noted that the tap extends out in front of the shoe at the front so as to guard as far as possible wear upon the insulating sole *b* which is also turned up at the side of the shoe all the way around as indicated in Fig. 1 to afford suitable insulation at the edges.

The upper is constructed of a top portion *f* of waterproof leather which has eyelets *g* that are mere perforations, and the whole shoe is kept free from any metallic devices whatever. A leather string *g* is used to lace the shoes.

The lower portion of the upper comprises a lower section *h* which extends completely around the shoe and occupies the greater portion of the lower portion, and which is a double insulated section. The purpose of using two strips *i* and *j* to insulate this portion of the shoe is not only to get a thicker substance at this point but for the very important object of avoiding the registry of blow-holes in the rubber as far as possible. Inasmuch as rubber easily breaks down when subjected to electric current at points where there are blow-holes, it is very important that the likelihood of blow-holes be eliminated if possible, and if it cannot wholly be eliminated, then protection be afforded against serious effects from such blow-holes. This I have accomplished by vulcanizing the two layers of rubber of high electrical efficiency. Inasmuch as the upper section of the lower portion of the shoe is not in a dangerous zone, the two-layer arrangement is not continued clear to the top for it makes the shoe more flexible and easier to walk in to have the upper section of the lower portion thin and flexible. The inside of the upper is provided with a fabric lining *k*.

It may be remarked before explaining how all these parts are fixed together, that the likelihood of blow-holes allowing the sole to break down is also considerably minimized by the reason of the vulcanization of three layers of rubber compounds, the rubber tap *a* of high wearing efficiency rubber, the insulating sole *b* of high electrical efficiency rubber, and the compound *c*, which is a filler made of scrap material. All these layers of rubber and fabric are vulcanized together by a suitable vulcanizing process, as for instance, by the use of high pressure and heat furnished by steam under pressure. However, I do not limit myself to any par-

ticular way of vulcanizing these various layers together.

It is very desirable to guard against mishap in every way possible in preserving life.

- 5 Consequently I have found it advantageous to construct my shoe of rubber of such color that it is not likely to be mistaken for other things. For instance, the uppers are constructed of a chocolate colored rubber as is 10 also the heel *c*, while the tap is constructed of white rubber compound. It is especially important that the tap and the insulating sole should be constructed of layers of rubber of different colors. To this end the insulating sole *b* is constructed of a chocolate colored rubber, the tap sole being constructed of white rubber compound. When the white top wears away and exposes the insulating sole, a visible warning is immediately given 15 to the user of the shoes or his employer that the danger point has been reached and that either the shoe should be repaired or thrown away.

I have found that a shoe constructed in 20 accordance with the above description will stand the test of over 30,000 volts without breaking down. It is obvious that when linemen are provided with these shoes, almost a constant precaution against death is 25 secured, as the use of the safety devices is not attendant upon the care of the lineman but on the contrary this insulating medium constantly attends him and protects him in all cases except where he deliberately takes 30 them off.

In the description and claims I speak of "rubber" having certain specified characteristics, but it will be understood that such substances are really rubber compounds and 35 suitable rubber compounds known as "rubber" having the specified characteristics can be obtained from any manufacturer of commercial rubber. Inasmuch as each manufacturer varies these compounds, the ingredients of each are not given.

Ordinarily electrical transmission lines carry 20,000 volts more or less and the material in my shoe is designed to resist such electrical currents without breaking down.

50 By the use of such terms as "high tension electrical currents" or similar expressions in the claims I means electrical currents substantially as high as 20,000 volts.

What I claim is:

- 55 1. A lineman's shoe, comprising an upper and a sole, the latter having an outer layer of a rubber compound having high wearing properties and an insulating layer of a rubber compound constructed for and 60 capable of resisting high tension electrical currents.

2. A lineman's shoe, comprising an upper and a sole secured thereto, comprising an outer layer of one color and thereabove an 65 electrical insulating medium calculated to

resist the passage of relatively heavy voltage electrical currents, said insulating medium being of a different color so that when the outer layer wears away the danger of wearing away the insulating medium is 70 indicated.

3. A lineman's shoe, comprising an upper and a sole, the latter comprising an outer layer of rubber compound of relatively high wearing efficiency and of a specified color, 75 and an inner insulating layer constructed of a rubber compound of a different color and having a relatively high electrical resistance.

4. A lineman's shoe, having an insulating sole and an upper, the lower portion of which is constructed of two layers having flat coinciding continuous surfaces which are vulcanized together, and which are each of a rubber compound possessing high electrical resistance properties. 80

5. A lineman's shoe, having an electric insulating sole and an upper, the lower section of the lower portion of which is constructed of two layers of high efficiency electrical-resistance rubber which are vulcanized together and the top section of which lower portion is constructed of a single layer of rubber having a relatively high electrical resistance. 90

6. A lineman's shoe, comprising an upper and a sole, the latter having an outer layer of a rubber compound having high wearing properties, an inner insulating layer of a rubber compound constructed for and capable of resisting high tension electrical currents, and a layer inside of the insulating layer constructed of filler material which is water-proof and lighter than solid rubber compound. 95

7. A lineman's shoe, having a sole and 100 the lower portion of the upper constructed of rubber including a complete ensheathing of a rubber layer of relatively high electrical current resisting properties.

8. A lineman's shoe, having a sole and 105 the lower portion of the upper constructed of rubber, some of which is calculated to resist high voltage currents, the said sole and lower portion of the upper being adapted to resist electrical currents as high as 110 20,000 volts more or less.

9. A lineman's shoe, the lower portion of 115 which is constructed of rubber adapted to successfully resist an electrical current of 20,000 volts more or less.

10. A lineman's shoe, having a portion 120 constructed of a plurality of layers, one of the layers being an insulating layer constructed of rubber compound calculated to resist high tension electrical currents and another layer being on the outside of such first-mentioned layer and of a different color than such first-mentioned layer so that when it wears away the exposure of the inner insulating layer is evident. 125

13. A lineman's shoe, having a portion
constructed of a plurality of layers, one of
the layers being constructed of a material
of high electrical resistance and another
5 layer on the outside of such first-mentioned
layer being constructed of a material of a
different color so that when the last-men-
tioned shoe wears away the fact is evident
10 from the visible exposure of the different
colored layer of high electrical resistance
properties.

14. A lineman's shoe, having in combina-
tion, an upper whose lower portion is con-
15 structed of material having high electrical
resistance properties and a sole having a
layer of material of high electrical resistance
properties which extends up at the edges
and laps the high resistance material of the
20 lower portion of the upper.

15. 16. A lineman's shoe, having in combina-
tion, an upper whose lower portion is con-
25 structed of material having high electrical
resistance, and a sole having a layer of ma-
terial of high electrical resistance which ex-
tends up at the edges and laps the high

electrical resistance material of the lower
portion of the upper and a layer of pro-
tecting material which underlies the layer
of electrical resistance material of the sole
and which extends up at the sides and over-
30 lies the lapped portions of the two high elec-
trical resistance materials.

17. A lineman's shoe, having a sole pro-
vided with a layer of material capable of
35 resisting high tension electrical currents and
means for preventing the exposure and wear
of such layer.

18. A lineman's shoe, having a sole pro-
vided with a layer of material capable of re-
sisting the high resistance currents used in
40 electrical transmission lines and an upper
whose lower portion has an ensheathing
layer of material capable of resisting high
resistance currents of electrical transmission
45 lines, the two said layers homogeneously
running together.

In testimony whereof, I sign this specifi-
cation.

HARRY E. MARSHALL.
